UNITED STATES PATENT OFFICE

113,383

DESIGN FOR A TYPIST'S DESK

Theodore T. Haag, Plainfield, N. J., assignor to Security Steel Equipment Corporation, Avenel,
N. J., a corporation of New Jersey

Application November 17, 1938, Serial No. 81,180

Term of patent 14 years

To all whom it may concern:

Be it known that I, Theodore T. Haag, a citizen of the United States, residing in the city of Plainfield, county of Union, and State of New Jersey, have invented a new, original, and ornamental Design for a Typist's Desk, of which the following is a specification, reference being had to the accompanying drawing, forming a part thereof, in which:

I claim:

The ornamental design for a typist's desk as shown.

THEODORE T. HAAG,
